Chas. P. Snow,
by W. B. Richards, Atty.

United States Patent Office.

CHARLES P. SNOW, OF FREEPORT, ILLINOIS.

Letters Patent No. 90,598, dated May 25, 1869.

IMPROVED WASHING-MACHINE.

The Schedule referred to in these Letters Patent and making part of the same.

To all whom it may concern:

Be it known that I, CHARLES P. SNOW, of the city of Freeport, in the county of Stephenson, and State of Illinois, have invented certain new and useful Improvements in Washing-Machines; and I do hereby declare that the following is a full, clear, and exact description of the same, reference being had to the accompanying drawings, making a part of this specification, in which—

Figure 1 is a top view.

Figure 2 is a longitudinal vertical sectional view.

Similar letters of reference indicate corresponding parts in both figures.

The nature of this invention relates to improvements in washing-machines, and the invention consists in the arrangement, within a suitable tank, of a series of connected rollers, mounted on springs; above which is pivoted, with a sliding pivot, two arms, carrying a corrugated rubber board, which may be given a rectilinear and an oscillating movement over the rollers, thereby assimilating very nearly the operation of hand-washing.

To enable others to understand the construction and operation of my invention, I will proceed to describe it, with reference to the drawings.

A represents a tank or suds-box, supported on the legs B.

C represents four pins, passing up through the bottom of the tank A, and held in place by the straps D, or their equivalent, on the bottom of box A.

E represents spiral springs, encircling the pins C a portion of their length.

d represents a rectangular frame, composed of the two side-pieces e e and the cross-pieces g, and being held in position by the pins C, and supported on the springs E, allowing vertical movement of the frame d, and facility for taking it out of the tank A when necessary.

J represents a series of rollers, having journals at each end and bearings in the side-pieces e e of the frame d.

L L represent levers, connected at their outer end by the cross-rod or hand-hold M, and pivoted by means of the pins n, at the other end, in the pulleys r r.

t represents recesses in the sides of the tank A, with a metallic way, w, fitted therein, with a face or track corresponding with the groove on the rim or periphery of the pulleys r which run in the same.

y represents semi-cylindrical slats, attached transversely to the levers L L, and presenting a corrugated surface on the under side, which constitutes the rubber-board, and which may be given a rectilinear movement over the rollers J by means of the pulleys r running in the ways w, the power being applied by hand at the hand-hold M.

The levers L, where the slats y are attached, are curved downward, in order to have the said slats arranged on a convex surface, for greater facility in passing over the articles being washed, and the levers, being pivoted at the pulleys r, may be given an oscillating movement, to still further facilitate the operation.

What I claim as my invention, and desire to secure by Letters Patent, is—

A rubbing-frame, consisting of the curved levers L, hand-hold M, slats y y, and rollers n, when constructed and arranged as shown, and operating in combination with the ways W, and spring-roller bed J J, with guides C, in the manner and for the purposes herein set forth and described.

Signed at Freeport, Illinois, this 4th day of December, 1868.

CHARLES P. SNOW.
